ROTARY GAS ENGINE.

Application filed April 3, 1925. Serial No. 20,338.

This invention relates to rotary engines of the internal combustion type and in its simplified form is particularly useful for automobiles, motor boats and other light vehicles.

5   Rotary gas engines in their usual form are not well adapted for use in light vehicles owing to their complicated construction and the prohibitive proportions which they usually assume.

10   Another difficulty incident to rotary engines prior to our invention is inaccessibility of the parts due to the number and design thereof making them impractical especially for use in automobiles.

15   It is, therefore, one of the objects of the invention to overcome such objections by reducing the number of parts to a minimum and at the same time making the parts which are subject to most wear removable and readily 20 accessible.

Another difficulty is that in rotary engines of this type it is necessary to maintain a sensible clearance between the rotor and the casing in which it runs. The amount of such 25 clearance is determined by the expansion and contraction of the metals due to the heat of the explosion and results in leakage of some of the compressed gases past the clearance and hence a loss or waste of considerable 30 power. Another object of this invention is to overcome this difficulty.

Still another object of the invention is to provide an engine in which all the power take off is taken directly from the rotor.

35   Still another object of the invention is to provide a simple and effective timing mechanism, direct in its distribution.

Still another object of the invention is to provide an engine in which each piston may 40 be made to fire an undetermined number of times per revolution by increasing the number of explosion chambers, hence practically giving a continuous flow of power.

Still another object of the invention is to 45 provide an engine in which the explosion chamber is defined by the casing and a vane or firing head on the reciprocating cylinder.

Still another object of the invention is to 50 provide an engine which is perfectly balanced at all speeds and loads.

Still another object of the invention is to provide an engine in which all the energy caused by the explosion of the charge is used from its highest combustion pressure to ap-

proximately atmospheric pressure at the exhaust, such energy being exerted tangentially from a common centre. 55

Still another object of the invention is to provide an engine in which the gyroscopic action thereof is utilized to stabilize and keep 60 the vehicle which it drives in equilibrium.

More generally our invention contemplates a simple, compact and efficient rotary gas engine and one which among other things, is suitable for use in light vehicles, is economical in gas consumption, easy to lubricate and effectively sealed against leakage of 65 pressures.

How the foregoing, together with such other objects and advantages as may herein-after appear, or are incident to our invention, are obtained is illustrated in preferred 70 form in the accompanying drawings of which

Fig. 1 is a cross-section of our engine with the reciprocating parts in elevation; 75

Fig. 2 is an enlarged section taken on the line 2—2 of Fig. 1;

Fig. 3 is a diagrammatic section showing a different position of the rotor and associated mechanisms and 80

Fig. 4 is a diagrammatic view of the timing mechanism and shows the wiring for a 4 cylinder engine having two explosion chambers.

Referring now to Fig. 1 the reference letter 85 A denotes the rotor of our engine, the letter B, the fixed casing surrounding the rotor, the letter C the reciprocating compression creating mechanism, and the letter D the central fixed shaft.

Each reciprocating compression creating mechanism C in this instance four, consists of a sleeve or cylinder 7 and a piston 8. The sleeves 7 and pistons 8 are reciprocated independently of one another by means of cam 95 and lever mechanisms, the pair of cams 9, 9 and levers 10, 10 operating on the sleeves and the pair of cams 11, 11 and levers 12, 12 operating on the pistons. The operating levers 10 and 12 are fulcrumed at one end on the pins 13 which are secured in the rotor A and have pin connections at their other ends with the sleeves and pistons, the levers 10 being connected to the sleeves 7 and the levers 12 to the pistons 8. Intermediate the ends of the levers are the cam rolls 14 which work in the cam grooves, said cams being of the face type. Since the sleeves and pistons work in 100 105

a straight line and since the levers are pinned thereto we have provided compensating slots 15 at the fulcrum ends of the levers. As the cams are subject to wear it may be desirable 5 to replace them, for which purpose they are detachably secured to the casing B, the inner cams 11, 11 being detachably secured to the outer cams 9, 9.

The engine has an axial intake port 16 in 10 the fixed shaft to which the manifold 17 of the source of fuel supply is connected. This port has a series of radial passages 18 communicating thru the medium of an annular groove 19 with the cored passages 20 in the 15 rotor A. These passages in turn communicate thru the medium of annular grooves 21 around the openings in which the reciprocating mechanisms are mounted with ports 22. Referring now to the position of the reciprocating parts shown in the right hand portion 20 of Fig. 3 it will be seen that as the sleeves or cylinders 7 reciprocate due to the action of the cam and cam levers a point is reached 25 where the ports 23 in the sleeves register with the ports 22 thus establishing communication with the source of fuel supply. Just prior to these ports coming into registry the piston 8 moves downward due to the action of its cam and lever creating a partial vacuum which 30 causes a charge of gas to be drawn into the space thus created between the sleeve and piston, when the ports register. The rotor in continuing its revolution causes the cam rollers to actuate the levers and reciprocating 35 parts to close the ports 22, the piston 8 travelling upward to compress the admitted charge. This position is shown to the left of Fig. 3.

In the embodiment shown we have provided 40 two firing chambers 24 oppositely located in the fixed casing B each of which is provided with a spark plug 25 for igniting the explosive charge and an exhaust port 24^a for discharging the burnt products of combustion. When the rotor has revolved to a 45 position so that two opposite sleeves 7 are in registry with the two firing chambers 24 the cam levers are actuated to cause the power heads 7^a of the sleeves to project into the 50 chamber thus affording a vane or firing head against which the forces of the explosion are directed. The firing chambers are here shown as grooves of semi-circular cross-section into which the heads of the pistons snugly fit when at their extreme positions. To 55 make a tight seal around the combustion space we have provided the sealing members 26 in the power heads 7^a of the sleeves and the peripheral sealing rings 27 and 28 between the rotor A and the casing B.

The compressed charge in the space previously described between the reciprocating parts is transferred to the combustion space E (see Fig. 1) by means of the double seated 60 spring actuated cylindrical valve 29. The

valve 29 is held against its lower seat 30 during compression by means of spring 31, bearing at its upper end against the valve cage 32 and at its lower end against the collar 33 in the valve stem 34. An additional spring 35 bearing against the collar 33 at its upper end and against the shoulder 36 in the piston rod 37 at its lower end neutralizes the pressure of spring 31 at a certain point of compression. Additional pressure on the spring 75 35 as the piston travels upward relieves the valve 29 from its lower seat 30 and allows the compressed charge to enter the combustion space E thereabove. As soon as this transfer has taken place the valve seats on its upper seat 38, due to the piston 8 being in its upper position and causing the spring 35 to be compressed in an amount which overcomes the action of the spring 31. Thus the charge is confined to the combustion space E for subsequent ignition. The above operation of the valve is reversed as the piston and sleeve recedes to intake.

The novel construction of the valve just described, its valve cage, its containing sealing 90 rings 29^a, sealing the cylindrical wall of the valve against the escape of compressed gases, and the combination of valve seats and ports for compressed charge outlet is an essential and important unit to the proper functioning 95 of the engine.

An important feature of this invention is the arrangement of the firing chamber with its spark plug and exhaust port which arrangement insures that every pound of energy 100 is used from its highest combustion pressure at the point of ignition to an approximately atmospheric pressure at exhaust. The projecting head of the sleeve receives the explosive charge on one side while the other side 105 serves to scavenge the firing chamber of burnt gases previously exploded therein. All danger of backfiring is eliminated by our construction. It will thus be seen that by arranging the firing chamber at the periphery 110 of the rotor the forces of the exploded gases are much greater due to their spending their forces in a radial direction from a common centre and tangentially thereto.

The timing of the ignition is accomplished 115 by means of the timing device shown in Figs. 2 and 4 which consists of a series of contact members 39, one for each reciprocating device, mounted on the master gear 40 which gear is detachably secured to the hub 41 of the rotor A. Secured to a bracket 42 on the fixed casing B are the terminal connections 43, 43 across which a circuit is completed when the contact members 39 are in contact therewith. The contact is made by the sliding shoe principle 120 insuring effective contact. With our arrangement of timer and method of spark distribution the distribution is direct without the use of reduction gearing or movable parts which would require oiling and be sub- 125 130

ject to wear. It is also to be pointed out that a single wire 44 is all that is needed to supply one or more cylinders with spark.

In conclusion our engine as above described eliminates a majority of reciprocating parts usually present in rotary engines; has a fixed casing which embodies firing chambers, exhaust ports, water chamber 45 for cooling the engine, spark plugs and terminal connection; and a rotor which receives all power impulses direct at its periphery, transmitting it directly to its own common centre, from which point power takes off including water pump, oil pump, starter and timer mechanism. By our arrangement the initial intake charge and the exhaust is controlled without the use of valves. The rotor is symmetrical in design it having a central hub portion A¹ mounted on anti-friction bearings, an outer rim like portion A² in which the reciprocating devices are mounted and an intermediate web portion A³ in which the gas passages are cored. The hub portion A¹ and the casing bearings at the extreme ends thereof are designed to prevent leakage of oil.

While we have described our invention in connection with an engine having four reciprocating mechanisms and two firing chambers it is to be understood that an important feature thereof is the way it lends itself to other combinations by which more power impulses may be had per revolution. As an example the diameter may be made such to accommodate eight cylinders and four firing chambers giving 32 power impulses per revolution, which is the equivalent in explosions to a 64 cylinder four cycle motor of equal bore and stroke.

In short a well balanced symmetrical engine is produced in which the gyroscopic action may be utilized to stabilize and keep the vehicle being propelled in equilibrium.

We claim:

1. In a rotary gas engine, the combination of a rotor, a stator, a radially disposed cylinder mounted for reciprocation in said rotor, a piston in said cylinder, means for actuating said cylinder and piston, an inlet for admitting gas into the cylinder for compression therein, a firing chamber in the stator one wall of which is defined by the rotor and another by said cylinder in its outward reciprocatory position, means for subsequently passing the compressed charge to said firing chamber, and means for igniting the charge.

2. In a rotary gas engine, the combination of a rotor, a stator, a radially disposed cylinder mounted for reciprocation in said rotor, a piston in said cylinder, and means for actuating said cylinder and piston to take in an explosive charge and afterwards compress it, together with valve means for controlling the admission of said charge and to subsequently control its discharge.

3. A rotary gas engine comprising in com-

bination a central fixed shaft, a rotor mounted thereon, a fixed casing surrounding the rotor, a piston and sleeve mechanism mounted for reciprocation in said rotor, an explosion chamber in the fixed casing, said sleeve mechanism having a position in which it projects into the explosion chamber, means for actuating said piston and sleeve to create a chamber into which the gas is drawn and in which compression subsequently takes place, means for transferring said compressed gas to the explosion chamber and means for igniting the transferred charge.

4. In a rotary gas engine, a rotor, a radially disposed reciprocating sleeve in the rotor having a firing head adapted to receive the force of the explosions substantially tangentially to the rotor, a reciprocating piston in the sleeve, means for actuating the sleeve to move its firing head into firing position and means for actuating the reciprocating piston to compress a charge of gas.

5. In a rotary gas engine, an explosion chamber, a rotor, a reciprocating member in said rotor, a reciprocating piston in said member, a double seated valve in the reciprocating member and means for changing the seating of the valve to control gas inlet to said chamber, said means being actuated as the pressure changes within said member.

6. A rotary gas engine comprising in combination a rotor, a fixed casing surrounding said rotor, a plurality of reciprocating cylinders and pistons, a plurality of explosion chambers in the fixed casing and means whereby the heads of the reciprocating cylinders are made to project into the explosion chambers as the cylinders register therewith.

7. A rotary gas engine comprising in combination a central fixed shaft, a rotor mounted thereon, a fixed casing surrounding the rotor, a sleeve mounted for reciprocation in said rotor, a piston mounted for reciprocation in said sleeve, a pair of like cams for actuating the sleeve through the medium of levers fulcrumed in the rotor and a pair of like cams for actuating the piston through the medium of levers fulcrumed in the rotor.

8. In a rotary gas engine, a rotor, a reciprocating sleeve in the rotor including a firing head adapted to receive the force of the explosions substantially tangentially to the rotor and a reciprocating piston in the sleeve for compressing a charge of gas, together with power take off means carried by the rotor.

9. A rotary gas engine comprising, in combination, a rotor, a fixed casing surrounding the rotor, a firing chamber in the casing, a cylinder in said rotor, means whereby the head of said cylinder is caused to project into said firing chamber, a reciprocating piston in said cylinder, means for delivering a charge of gas to the cylinder for compression therein and valve means actuated as the pres-

sure increases in said cylinder for transferring the compressed charge to the firing chamber.

10. In a rotary gas engine, the combination of a stator, a rotor, a firing chamber in the stator, a reciprocating cylinder housed in said rotor having a firing head adapted to project into said chamber, a reciprocating piston in said cylinder, means for admitting 5 a charge of gas to said cylinder for compression by said piston, a valve associated with said cylinder for controlling admission of a compressed charge from said cylinder to its firing head, and spring means cooperating 10 with said valve and piston to cause the valve to admit a compressed charge of gas to the firing head when the piston has substantially completed its compression stroke.

11. A rotary gas engine comprising in com-

bination a central fixed shaft, a rotor mounted thereon, a fixed casing surrounding the rotor, a piston and sleeve mechanism mounted for reciprocation in said rotor, a firing chamber having fixed walls defined by the casing and the rotor and a movable wall defined by the sleeve mechanism when in a predetermined position, means for actuating said piston and sleeve to create a chamber into which the gas is drawn and in which compression subsequently takes place, means for passing said gas to the firing chamber, and means for exploding the charge when the sleeve mechanism is in position to constitute the movable wall of the firing chamber.

In testimony whereof, we have hereunto signed our names:
